Primary Examiner—A. Hugo Word*Assistant Examiner*—Paula Mortimer*Attorney, Agent, or Firm*—Dick and Harris[57] **CLAIM**

The ornamental design for a giant gumball dispensing machine, as shown and described.

DESCRIPTION

FIG. 1 is a front perspective view of a giant gumball machine dispensing machine showing my new design; FIG. 2 is a front elevational view thereof; FIG. 3 is a rear elevational view thereof; FIG. 4 is a side elevational view thereof; FIG. 5 is an opposite side elevational view thereof; FIG. 6 is a top plan view thereof; and, FIG. 7 is a bottom plan view thereof.
The broken line showing of the individual gumballs is for illustrative purposes only and forms no part of the claimed design.
